UNITED STATES PATENT OFFICE.

GEORGE J. FANNER, OF CLEVELAND, OHIO, ASSIGNOR TO THE FANNER
MANUFACTURING COMPANY, OF SAME PLACE.

DESIGN FOR AN ICE-TOOL.

SPECIFICATION forming part of Design No. 27,210, dated June 15, 1897.

Application filed April 26, 1897. Serial No. 634,045. Term of patent 31 years.

To all whom it may concern:

Be it known that I, GEORGE J. FANNER, of Cleveland, Cuyahoga county, Ohio, have invented and produced a certain new and useful Design for Ice-Tools; and I do hereby declare the following to be a full, clear, and exact description of the invention, such as will enable others skilled in the art to which it pertains to make and use the same.

10 My invention relates to a new design for ice chisel and pick; and it consists in the peculiar conformation of the same, as will be hereinafter more fully set forth and claimed.

In the drawings, Figure I is a view in elevation illustrating the tool, showing the same with the flat side of the chisel or shaver. Fig. II illustrates the tool, showing it when looked at from the edge of the shaver or chisel.

15 A represents a handle, which is in outer contour of the usual conformation and is provided with open barwork *a b*. To the lower end of the handle A is secured a chisel por-

tion B, the upper contour of which is formed in the shape of the arc of a circle, as at C, the lower or cutting edge being formed sharp or 25 chisel-shaped and provided with saw or serrated teeth D. The upper end of the handle is provided with a cylindrical projecting portion E, chisel-shaped, as at E', at its upper end.

The essential features of my design consist 30 in providing the handle at one end with a flat chisel-shaped portion B and at the opposite end with the pointed cylindrical portion E.

What I claim is—

The design for an ice-tool as shown in the 35 drawings and described in the specification.

In testimony whereof I sign this specification, in the presence of two witnesses, this 10th day of April, 1897.

GEORGE J. FANNER.
